United States Patent Office

Des. 214,081
Patented May 6, 1969

214,081

HIGH-INTENSITY LAMP OR SIMILAR ARTICLE

Minoru Araki, Tokyo, Japan, assignor to Lloyd's Electronics International, a corporation of California

Continuation-in-part of design application Ser. No. 86,965, Sept. 13, 1965. This application Jan. 10, 1966, Ser. No. 1,856

Claims priority, application Japan May 14, 1965

Term of patent 14 years

Int. Cl. D26—02

U.S. Cl. D48—20

FIG. 2.

FIG. 1.

FIG. 3.

FIG. 4.

FIG. 6.

FIG. 7.

FIG. 5.

FIG. 8.

FIG. 9

FIG. 10.

FIG. 11.

FIG. 12.

FIG. 13.

FIGURE 1 is a side elevational view of a high-intensity lamp incorporating my new design and shown in a typical extended operating position;

FIG. 2 is a front elevational view thereof;

FIG. 3 is a top plan elevational view thereof;

FIG. 4 is a rear elevational view thereof;

FIG. 5 is a bottom plan view thereof;

FIG. 6 is a sectional view taken along a plane corresponding to line 6—6 of FIG. 1;

FIG. 7 is a side elevational view of the lamp shown in closed position;

FIGS. 8, 9 and 10 are front, side and top plan elevational views of a modified form of the present invention; and

FIGS. 11, 12 and 13 are front, side and top plan elevational views of another modified form of the present invention.

The rim at the end of the reflector housing in all forms of the invention is translucent.

This is a continuation-in-part of design application Ser. No. D86,965, filed Sept. 13, 1965, and now abandoned.

I claim:

The ornamental design for a high-intensity lamp or similar article, substantially as shown and described.
